UNITED STATES PATENT OFFICE.

HARTLEY O. BAKER, OF PUEBLO, COLORADO, ASSIGNOR TO THE BAKER STEAM MOTOR CAR AND MANUFACTURING CO., INC., OF PUEBLO, COLORADO.

AUTOMATIC FLUID-CONTROLLER.

1,354,373.

Specification of Letters Patent. Patented Sept. 28, 1920.

Application filed January 3, 1919. Serial No. 269,433.

To all whom it may concern:

Be it known that I, HARTLEY O. BAKER, citizen of the United States, residing at Pueblo, in the county of Pueblo and State 5 of Colorado, have invented certain new and useful Improvements in Automatic Fluid-Controllers; and I do hereby declare the following to be a full, clear, and exact description of the invention, such as will enable others skilled in the art to which it 10 appertains to make and use the same.

The present invention is an automatic controller for regulating the supply of liquid or other fluid, as in a water boiler or steam 15 generator, such as disclosed in the application for patent on water boiler, filed even date herewith, Serial No. 269,432. This application relates to the features of the automatic fluid controller which is disclosed 20 in said application for patent on water boiler, it being understood that the controller herein disclosed can be used for various other purposes than in the relation to a water boiler as described and illustrated 25 in the sister application.

It is the object of the invention to provide a novel and improved automatic controller including a thermostat and valve or other controlling device operated by the 30 thermostat, and including such a novel combination and arrangement of the component parts, that the device will be highly efficient and practical for use in water boilers and other contrivances.

35 A further object is the provision of such an automatic controller having a compound action, in order that it will be sensitive, provision being made whereby an accurate adjustment can be obtained to regulate the 40 opening and closing of the valve at desired or predetermined temperatures.

It is also within the scope of the invention to provide an automatic controller of the nature indicated which is simple in construction easy to manufacture, and which can be readily installed on various boilers or other appliances.

With the foregoing and other objects in view which will be apparent as the description 50 proceeds, the invention resides in the construction and arrangement of parts hereinafter described and claimed, it being understood that changes can be made within

the scope of what is claimed without departing from the spirit of the invention. 55

The invention is illustrated in the accompanying drawing, wherein:—

Figure 1 is a side elevation of the improved controller, showing the valve disposed in the by-pass or shunt as disclosed 60 in the other application referred to, although it will be understood that the controller is not limited to this particular use.

Fig. 2 is a longitudinal section of the valve taken on the line 2—2 of Fig. 1. 65

The valve 1 and thermostat 2 are in substantial parallel relation as shown, and the valve comprises a casing 3 having lateral nipples or connections 4 for pipes 5 and 6, said casing being provided with a valve seat 70 7 between said nipples or ports. A valve stem 8 is slidable through one end of the casing 3, said end of the casing being preferably provided with a stuffing box or packing 8^a embracing the stem 8 to prevent leakage and a bifurcated member 9 is threadedly or otherwise engaged on the stem 8 at the outer end thereof, being held in any adjusted position by means of a lock nut 10 on the stem. This provides for the adjustment of the controller, it being noted that when the nut 10 is loosened, the member 9 and valve stem 8 can be adjusted relatively to determine the temperature at which the valve will open and close. The opposite 85 end of the casing 3 has a bifurcated portion 11, and at the two extremities of the valve, levers 12 are pivoted within the bifurcated portions as at 15.

The levers 12 constitute the connections 90 between the thermostat and valve, a link or non-movable stay 15 being pivoted as at 14, to the levers 12 to provide fulcrums therefor. The stay or strut 15 is connected to the levers 12 near those ends which are 95 farthest away from the valve, so that the valve is connected to and located between the long arms, while the thermostat 2 is connected to and located between the short arms of the levers thus obtaining a larger 100 relative movement of the parts of the valve than of the thermostat.

The thermostat 2 comprises an expansion and contraction tube 16 substantially parallel with the valve and located at that side 105 of the stay 15 opposite to the valve. The

ends of the tube 16 are closed and bifurcated, and are pivoted as at 17 to the short arms of the levers 12. Thus, the expansion and contraction of the tube 16 will swing the short arms of the levers away from and toward one another, respectively, and this motion is amplified at the end of the long arms of the levers to which the valve is connected. Pipes or tubes 18 are connected to the expansion tube 16 near its opposite ends for conducting water, steam or other fluid through the tube 16, to control the valve 1. In a water boiler or steam generator, the pipes 18 can be so connected thereto that water or steam flows through the tube 16, to control the supply of water to the boiler, but, as above indicated, this controller can be used for other purposes wherein the temperature of fluid flowing through the tube 16 controls a valve or equivalent device for any other purpose. As shown in Fig. 1, the pipe 6 leads to a water tank or reservoir 19 from which the water is pumped by pump 20 through a pipe 21 leading to the boiler (not shown), the pipe 21 having a pressure check valve 22 therein requiring a predetermined pressure of the water before it can flow on through to the boiler. The pipe 5 is connected to the pipe 21 between the pump 20 and pressure check valve 22, so that when the valve is opened the water will flow through the by-pass, comprising the pipes 5 and 6, back to the tank 19, since the pressure will not rise sufficiently to open the valve 22. However, when the valve is closed, the water cannot flow through the by-pass, and the pressure will therefore accumulate and force the valve 22 open for the flow of water past said valve.

In operation, as the tube 16 expands and contracts, this will close and open the valve, respectively, with the arrangement as shown, and the pivots 13 will naturally move through a proportionately larger distance than the pivots 17 at the ends of the thermostat. When the tube 16 expands, this separates the short arms of the levers, and moves the long arms thereof toward one another, so that the valve casing 3 and valve stem or member 8 are moved toward one another to seat the valve and close the passage therethrough. Conversely, when the tube 16 contracts, this separates the long arms 12 of the levers and thereby separate the valve seat 7 and stem 8 to open the passage through the valve. The levers 12 provide a compound action, and by thus connecting opposite ends of the tube 16 and parts of the valve with the link or stay 15 between the valve and tube, this provides an admirable arrangement because the component parts of the controller are a complete unit in themselves, and require no special supporting frame or base, it only

being necessary to connect the thermostat 65 and valve in their respective pipes or conduits.

Having thus described the invention, what is claimed as new is:

1. An automatic controller comprising a 70 thermostat, a stay, a pair of levers pivoted to opposite ends of said thermostat and to said stay and having ends movable toward and away from one another by the change in length of the thermostat relatively to said stay, and a controlling means having a pair of members movable relatively to one another, and relatively to the thermostat, one of said members being connected to one lever for movement therewith and the other 75 member being connected to the other lever for movement therewith.

2. An automatic controller comprising a 80 thermostat, a stay, a pair of levers pivotally connected with opposite ends of the thermo- 85 stat and with said stay to be swung toward and away from one another by the change in length of the thermostat with respect to the stay, and a controlling valve having a casing and valve member, the casing being 90 connected to one lever to move therewith and the valve being connected to the other lever to move therewith.

3. An automatic controller comprising an 95 expansion tube having a fluid inlet and a fluid outlet, a stay, a pair of levers pivotally connected to the opposite ends of said tube and stay and having ends movable toward and away from one another due to the change in length of the tube with respect to 100 the stay, and controlling means including a pair of relatively movable members individually pivoted to the portions of the levers to be moved individually with said levers.

4. An automatic controller comprising an 105 expansion tube having a fluid inlet and a fluid outlet, a stay parallel with said tube, and a pair of levers pivotally connected with the opposite ends of said tube and stay and having ends moved toward and away from one another by the change in length of the tube with respect to the stay, and a controlling valve parallel with said tube and stay having a casing and valve member 110 movable relatively to one another and relatively to said tube and stay, said casing and valve member being pivotally connected to said ends of the levers to be individually moved therewith.

In testimony whereof I have signed my name to this specification in the presence of two subscribing witnesses.

HARTLEY O. BAKER.
